UNITED STATES PATENT OFFICE.

FREDERICK ARTHUR TURNER, OF LONDON, ENGLAND.

FOOTBALL, PUNCH BALL, NET BALL, AND THE LIKE.

Application filed November 10, 1921. Serial No. 514,239.

To all whom it may concern:

Be it known that I, FREDERICK ARTHUR TURNER, a subject of the King of Great Britain and Ireland, residing at London, England, have invented certain new and useful Improvements in Footballs, Punch Balls, Net Balls, and the like, of which the following is a specification.

This invention relates to balls for playing football, punchball net ball and the like games.

It is well known in the case of balls for these games of the type having an outer leather or canvas case or cover, enclosing an inner inflatable bladder or ball, that it is often very difficult effectively to close the aperture in the outer case after inflation to the required degree of hardness, so as to properly protect the inner bladder or ball, and that it is also difficult to secure the lace, where such is employed, so that its ends do not protrude, which may cause accident.

In order to close the aperture in the cover of balls of the foregoing description, it has already been proposed to provide strips of leather or other material, each strip being attached at one end to the interior of the casing, at or close to the edge of the aperture, and at the other end, also to the interior 30 of the casing, at the other side of the aperture and at some little distance therefrom.

The object of the present invention is an improved arrangement whereby the edges of the aperture are drawn together in a more effective manner and are less likely to project from the peripheral surface of the ball than has been the case with previous constructions.

According to my invention, I provide a casing having an aperture of the usual form and I furnish bands, strips, cords or the like, each of which is attached to the outer cover or casing at three places, namely at one end to the interior of the cover or casing at some 45 distance from the aperture, at the other end to the interior of the cover or casing, at the other side of the aperture, and again intermediate its ends to the interior of the cover or casing at or in close proximity to one edge

of the aperture. I prefer that the adjacent bands, strips, cords or the like shall be attached alternately to opposite sides of the edge of the aperture.

This arrangement is found to give a particularly advantageous result as the radial pressure upon the portion of the band, strips or the like between the edge where it is attached and the end on the same side counteracts a tendency for the edge to be pulled or turned outwards which is found to exist in some cases where the strip or the like is simply attached near the edge.

A somewhat similar advantageous result may be obtained in a modified construction, in which I employ one or more bands or strips, the ends of each strip being attached to the opposite edges of the aperture and the strip extending completely around the inner periphery or surface of the outer cover or casing, to which it may be attached by stitching or otherwise. As compared with previous constructions of the kind before mentioned, it is to be observed that with my construction I provide a complete band passing around the interior of the cover and attached at each end to the edges, whereas with the prior construction separate bands were provided for each edge, attached at two points namely at one end to the edge and at the other end to the inner cover or casing on the other side of the aperture and at some little distance therefrom.

In order that the invention may be more clearly understood, reference is made to the accompanying drawings, which show, by way of example, two methods of carrying the invention into effect as applied to an ordinary football.

Fig. 1 is a plan view of the football.

Fig. 2 is a part transverse section on the line 2—2, Fig. 1.

Fig. 3 is a vertical transverse sectional view of the upper portion of Fig. 2, to an enlarged scale.

Fig. 4 is a diagrammatic illustration of the modified method of carrying the invention into practice.

In the construction illustrated in Figs. 1

to 3, the outer leather case *a* is formed of a number of sheets or strips of leather *a'* sewn together at *a*² in the usual well known manner. The case is also provided with the usual elongated slot or aperture *b* through which the inner india-rubber ball is inserted as is well known.

Located within the case *a* are a series of bands, strips, cords or the like *c*, *d*. The bands *c* and *d* are each attached as for instance by one or more rows of stitches to the inner surface of the outer case *a* at three points. The bands *c* are attached intermediate their ends to the edge *b*¹ of the aperture and at their ends at the point *e*, *e* to the casing, whilst the bands *d* are attached intermediate their ends to the opposite edge *b*² of the aperture *b*, and at their ends at the point *e*¹, *e*¹ of the casing. The length of the bands between the three points of attachment to the outer case is preferably equal to or slightly less than the circumferential length of the inner surface of the outer case between the corresponding points thereof, when the ball is inflated.

By this arrangement when the inner ball is inflated, the bands are pressed tightly against the inner surface of the outer case and the pressure exerted by the inner ball causes the edges *b*¹, *b*² of the aperture *b* to be drawn closely together.

By attaching the ends of the bands *c* and *d* to the case on opposite sides of and at points some distance from the aperture the pressure exerted by the inflated ball is distributed in such a manner as to prevent distortion of the ball when fully inflated whilst by arranging the bands *c* and *d* in pairs as shown the pull on the sides of the aperture *b* is more evenly distributed over its length consequently the tendency for the aperture to become distorted is eliminated.

The length of the portions of each of the bands or strips between their ends and the point of attachment to the edge of the aperture *b* need not necessarily be equal, furthermore the strips *c*, *d* instead of being arranged alternately as shown may be arranged in any other suitable manner. Similarly three or more than four strips or bands may be provided if necessary.

Referring now to the construction illustrated in Fig. 4, *g* is a band, strip or cord having a length corresponding to or slightly less than the circumferential length of the inner surface of the ball. The strip *g* is attached at opposite ends *g*¹, *g*² to opposite sides of the aperture *b* whilst intermediate its ends it is attached to the case, at one or more points; the drawing showing the same attached to the case at a point *g*³ situated approximately diametrically opposite the aperture *b*. The action when the inner ball is inflated is substantially the same as that described with reference to Figs. 1 to 3.

Although I have shown only one band or strap *g* in Fig. 4, I prefer to employ two or more so that the closing pull on the sides of the aperture *b* is more equally distributed.

The straps *g* may be either substantially parallel or they may be crossed or arranged in any other suitable manner.

The bands or strips *c*, *d* and *g* are preferably formed of a material such as webbing or the like flexible material, which will be practically unstretchable.

The edges of the aperture *b* may if desired, be provided with flaps or the like which are drawn up beneath the edges of the aperture when the ball is inflated.

What I claim as my invention and desire to obtain by Letters Patent of the United States of America is:—

1. In a football, punchball, net ball or the like, the combination of an outer cover, provided with an aperture, an inner inflatable ball and means for automatically closing the aperture in the cover as the ball is inflated, said means comprising a flexible non-stretchable member located within said cover, said member being attached at its ends to the cover on opposite sides of and at some distance from the aperture and intermediate its ends to the cover in the neighbourhood of one edge of said aperture, for the purposes set forth.

2. In a football, punchball, netball or the like, the combination of an outer cover provided with an aperture, an inner inflatable ball and means for automatically closing the aperture in the cover as the ball is inflated, said means comprising flexible non-stretchable members located within the cover, said members being attached alternately intermediate their ends to opposite edges of said aperture and at their ends to opposite sides of and at some distance from said aperture, for the purposes set forth.

3. A football, punchball, netball, or the like comprising an outer cover, an aperture in said cover, an inner inflatable ball, and means for automatically drawing the edges of said aperture together as the ball is inflated, said means comprising a plurality of flexible non-stretchable members, each attached at its ends to the interior of the cover at points thereof located on opposite sides of and at some distance from said aperture and attached to one edge of said aperture intermediate its ends, the length of said members between the point of attachment to said edge and the point of attachment to the cover on the opposite side of said aperture being less than the circumferential length of the cover between the corresponding points thereon, for the purposes set forth.

4. A football, punchball, netball or the like comprising an outer cover, an inner

inflatable ball, an elongated aperture in said cover, and means for automatically closing said aperture as the ball is inflated, said means comprising a plurality of flexible non-stretchable strips, arranged in pairs, each strip of each pair being secured at each end to the interior of the cover on opposite sides of and at some distance from said aperture and the strips of each pair 10 being secured intermediate the ends thereof

to opposite edges of said aperture, for the purposes set forth.

In testimony whereof I have hereunto affixed my signature this 24th day of October, 1921.

FREDERICK ARTHUR TURNER

In the presence of—

H. ROWLEY,
A. E. VIDAL.
